END FACING AND CENTERING MACHINE

John E. Lovely, Springfield, Vt., assignor to Jones & Lamson Machine Company, Springfield, Vt., a corporation of Vermont

Application March 24, 1933, Serial No. 662,482

14 Claims. (Cl. 29—27)

This invention has for an object to provide a machine for end facing and centering the ends of shafts, bar stock, and the like preparatory to turning the work as in an automatic lathe. To this end means are provided for holding the work and while it is so held to face off its ends to exact length and then to center drill to a uniform depth, these operations being automatically effected.

For a more complete understanding of this invention, reference may be had to the accompanying drawings, in which,

Figure 1 is a front elevation of the machine.

Figure 2 is a top plan of the same.

Figure 3 is a tail stock end elevation.

Figure 4 is a detail section on the line 4—4 of Figure 1.

Figure 5 is a fragmentary rear elevation showing a portion of the work head spacing mechanism.

Figure 6 is a detail section on the line 6—6 of Figure 5.

Figure 7 is a detail section on the line 7—7 of Figures 1 and 10.

Figure 8 is a vertical section on the line 8—8 of Figure 1.

Figure 9 is a detail section on the line 9—9 of Figure 7.

Figure 10 is a longitudinal section on line 10—10 of Figure 8.

Figure 10a is a detail section completing the section of Figure 10.

Figure 11 is a detail vertical section on line 11—11 of Figure 8.

Figures 12 and 13 are detail sections on the correspondingly numbered section lines of Figure 3.

Figure 14 is a fragmentary rear elevation of the head stock end of the machine.

Figure 15 is a head stock end elevation.

Figure 16 is a transverse section to a larger scale than Figure 4 showing the work gripping mechanism.

Figure 17 is a detail section on line 17—17 of Figure 16.

Figure 18 is a diagrammatic detail of a portion of the speed changing mechanism within the head stock.

As shown the machine comprises a base 1 having a head stock portion 2 and a tail stock portion 3 upstanding therefrom. Between these head and tail stocks is movably mounted a work carrier 4 which, as shown, is in two parts each carried by a rockable bar 5 journaled at opposite ends in the lower portions of the head and

tail stocks and held against endwise movement by stop collars 5a at opposite ends. Both the head and the tail stocks carry end facing tools shown as end mills 6 and 7, and center drills 8 and 9, and the workholder is manipulated to present the work in succession to the end facing tools to be cut off by them to exact predetermined length and to face the ends of the work, and then to the center drills which are actuated to center drill the faced work. In order that the work may be faced to adjustable predetermined length provision is made by which the spacing of the head and tail stocks may be adjusted. To this end, the tail stock is slidably supported on ways 10 on the base 1, as shown best in Figure 3, and for the purpose of effecting such adjustment a bracket 11 (see Figure 5) is secured to the tail stock as by bolts 12 and has a depending threaded sleeve portion 13 at its lower end through which is threaded an adjusting screw 14. This adjusting screw is shown as enclosed within a housing 15 (see Figure 2) extending along the rear side of the base 1, the screw being journaled in brackets 16 and 17 secured to the base 1. The tail stock end of the screw 14 is provided with a reduced squared extremity 18 to which may be applied when desired a crank member 19 (see Figure 2) by which this screw may be turned to thus adjust the position of the tail stock along the bed. 30

Facing tool mounting

The end facing tools shown as the mills 6 and 7 are fixed to shafts or spindles 30 and 31 respectively in the head and tail stocks, these being in spaced axial alignment, each mill itself being carried by a suitable tool holder 32 carried by its respective shaft, as shown in Figures 11 and 12. To this shaft 30 is keyed a gear 33 (see Figure 11) with which meshes a pinion 34 on a shaft 35 (see Figures 8 and 10) arranged in the head stock in parallel relation to the shaft 30. This shaft 35, as shown best in Figure 10, also has keyed thereto a gear 36 with which meshes a pinion 37 on a shaft 38 also parallel with the shaft 35 and the tool spindle 30. This shaft 38, as will later appear more in detail, is connected through to the tail stock for driving the opposite end mill 7 and also the center drill 9. This shaft 30 may be driven at any one of three speed ratios from a shaft 40 arranged parallel therewith, and which is the main drive shaft of the machine. This shaft 40 has slidably keyed thereon the gear sleeve 41 which has three gear portions 42, 43, and 44, which may be selectively meshed with the gears 55

45, 46 and 47 keyed to the shaft 38. The gear sleeve 41 may be moved to any of its operative positions by a gear shifting fork 48 riding in a groove 49 therein, this gear shifting fork, as shown best in Figure 18, being carried at the extremity of an arm 50 secured to a rock shaft 51 which extends transversely of the axis of the shaft 40 and extends out through the forward face of the head stock housing 52. It has secured on its outer end an actuating lever 53 provided with a detent handle 54 which may be engaged in any one of three recesses 55 in an arcuate member 56 secured to the forward face of the head stock housing, as shown best in Figure 1 to hold the screw 41 in any selected of its three operative positions.

Outwardly of the head stock housing this shaft 40 has journalled thereon a drive pulley 60 which may be clutched to the shaft 40 as by means of a ring friction clutch mechanism indicated generally at 61 within the hub 62 of the pulley. This friction clutch may be actuated to clutch or unclutch the pulley 60 to the shaft 40 by axial motion of a rod 63 slideable axially within the shaft 40 and which is provided with a recess 64 into which clutch actuating dogs 65 extend. On the inner end of the bar 63 is journalled a sleeve 67 provided along one side with suitable rack teeth (see Figures 7 and 9) with which meshes a mated pinion 68 secured to a rock shaft 69. This rock shaft extends laterally through the head stock casing 52 and on its rear face has secured thereto a forked arm 70 which is connected through a pin 71 to a block 72 (see Figure 2) adjustably connected to a rod 73 which forms part of the automatic stop mechanism of the machine as will later appear. A spring 75 secured at one end to the block 72 is secured at its other end as at 76 to the head stock casing 52 and tends to move the clutch rod 63 into clutch released position. As shown best in Figure 14, the opposite end of the rod 73 is pivoted to a brake actuating arm 80 which is connected to a band brake 81 surrounding a brake drum 82. This drum is secured to a shaft 83 which is driven from the shaft 40 through intermeshing bevel gears 85 and 86 on the shaft 83 and the shaft 40 respectively within the head stock casing 52. The forward end of the rock shaft 69 has secured thereto a clutch actuating lever 90 by which the stopping and starting of the machine may be manually controlled. Means are also provided which will later be described for effecting automatic stopping of the machine at the end of the machine cycle.

The end facing tool 7 at the tail stock end of the machine is mounted similarly to the tool 6 on the tail stock spindle 91 and is driven in the same direction, as shown in Figure 12. To this spindle 91 is keyed a gear 92 with which meshes a pinion 93 (see Figures 3 and 13) on a stub shaft 94. Keyed to this stub shaft is a gear 95 which meshes with a pinion 96 on a sleeve 97 journalled for rotation and through which extends a shaft 98 which forms a continuation of the shaft 38 in the head stock and which is coupled thereto by a coupling 99.

Work center drilling mechanism

The center drill 8 at the head stock end of the machine, as best shown in Figure 11, is carried by a spindle 100 rotatably mounted in sets of ball bearings 101 in a sleeve 102 which is mounted for axial movement so as to move the spindle 100 axially therewith. Splined to the spindle 100 at

its opposite end is a sleeve 103 which has fixed to or integral therewith a pinion 104 with which meshes a gear 105 (see Figure 10) keyed to the rear end of the shaft 35 and by this geared connection the spindle 100 is rotated. The rear end of the spindle 100 is shown as threaded at 106 and on this threaded portion is shown in Figure 11 a split stop collar 107. This collar may be clamped in any adjusted position on the threaded portion 106 as by means of the clamp screw 108 and limits the axial motion of the spindle 100 in drill feeding direction. Axial motion of the sleeve 102 which produces similar motion of the center drill 8 so as to feed the center drill into the work and then retract it from the work is produced by the rocking of a rock shaft 110 which has clamped thereto a gear segment 111 having teeth meshing with rack teeth 112 in the sleeve 102. Also meshing with the segment 111 is a similar but shorter segment 113 carried by a rock shaft 114. This rock shaft 114 has clamped thereto an actuating arm 115 on the outside of the machine as shown in Figure 1, to the lower end of which is pivotally connected as at 116 a rod 117 which extends toward the tail stock end of the machine where it is pivotally connected as at 118 with an arm 119 carried by a transverse rock shaft 120 (see Figures 1 and 3). This shaft 120 also has fixed thereon a cam follower arm 121 which has at its upper end a follower roll 122 for cooperation with cams 123 and 124 on a cam drum 125. This cam drum is secured to a cam shaft 126 which extends lengthwise of the machine beneath the head and tail stocks and carries a cam drum 127 beneath the head stock by which various other machine controls are effected as will later appear.

The tail stock center drill 9, as shown best in Figure 12, is carried by a spindle 130 quite similar to the spindle 100 and which is mounted in ball bearings 131 in a sleeve 132. This sleeve is also mounted for axial sliding motion and this is effected by rocking of a segment 133 carried by a rock shaft 134, the segment having teeth meshing with rack teeth 135 in the sleeve 132. On the rear end of the spindle 130 is mounted a stop collar 136 similar to the stop collar 107 on the spindle 100. The rock shaft 134 extends at one end outwardly of the machine casing as shown in Figure 1 and has secured thereto an arm 137 which is pivotally and adjustably connected at 138 with a rod 139 which is pivoted at the head stock end of the machine as at 140 to the arm 115. In order to permit suitable lengthwise adjustment of the arm 137 to the rod 139, this rod is shown as slotted at 142 to take the pivotal connection 138. This rod is also provided with an adjusting turnbuckle 143, the rod itself comprising endwise positioned portions connected together by this turnbuckle in order to provide for minor length adjustments as may be found necessary. With this interconnection between the two spindles, the center drills 8 and 9 are moved simultaneously toward and then from each other to center drill opposite ends of the work and then retract therefrom, the stop collars ensuring that the center drilling is effected to a uniform depth at each actuation.

The spindle 130 is slidably keyed within a sleeve 150 (see Figure 12) which is journalled in the machine frame in ball bearings 151 and this sleeve carries or has formed integral therewith a pinion 152. With this pinion meshes a gear 153 on a shaft 154 (see Figure 13) journalled in the ball bearings 155 and 156, and to this shaft 154 is keyed a gear 157 with which meshes a gear 158 keyed to the shaft 94 which, as previously de-

scribed, is driven from the head stock through the shaft 93. The drill 9 is thus driven in the reverse direction to the drill 8 since it is driven through the two intermediate shafts 94 and 154 from the 5 drive shaft 93 while the drill 8 is driven from the corresponding drive shaft 38 through the single intermediate shaft 35. As, however, the center drills face in opposite directions this reverse driving direction permits the drills to be used inter- 10 changeably so that but a single type standard centering drill is used at both ends of the work. Since right and left hand milling cutters are both standard one of each is used for the end facing tools, these tools being driven in the same direction 15 as previously described.

Work handling mechanism.

As previously pointed out the workholder 4 is made in two identical parts both carried by a 20 rock shaft 5. This permits spacing adjustment to suit the spacing between the head and tail stocks, the work being grasped adjacent to each end. Each workholder part, as shown best in Figures 4 and 16, is provided with a pair of 25 aligned slides 170 and 171 mounted for movement transversely of the axis of the rock shaft 5 and connected together for simultaneous motion by means of a double ended screw 172 passing therethrough, opposite end portions of this rod being 30 reversely threaded and carrying thereon nuts 173 and 174, respectively, which are suitably secured in the end portions of the slides 170 and 171. Opposite reduced extremities of the shaft 172 are journalled in bearings 175 and 176 re- 35 spectively, secured to opposite ends of the carriage 4 as by the bolts 177 and 178. As shown, the bearing 176 forms part of a support for a torque motor 179, the shaft 180 of which is mounted transversely to the shaft 172 and carries there- 40 on a worm 181 meshing with a worm gear 182 which is journalled on a stub shaft 183 in axial alignment with the screw 172. This worm gear 182 has pinned thereto a clutch element 184 having teeth meshing with a clutch element 185 mounted on the squared extremity 186 of the 45 shaft 172. This construction permits the shaft 172 to be rotated by the torque motor when desired, or by removing the bearing member 176 with the torque motor and the worm wheel 182 and then removing the clutch element 185, the 50 squared extremity of the shaft 172 is exposed for engagement therewith of a hand crank by which the shaft 172 may be rotated. Each of the slides 170 and 171 carries a suitable work gripping jaw 55 such as 190 and 191 for grasping the work adjacent to an end leaving the end face of the work free to be faced off and center drilled. One of these jaws such as 190 is shown as provided with a single V-shaped member which may pass be- 60 tween spaced V-shaped members of the other jaw 191, as shown best in Figures 2 and 4, thus to permit the engagement of various sized pieces of work 200 therebetween these partslapping past each other when the work is of small dia- 65 meter as shown in Figure 4, large diameter work being shown in Figure 16. Where torque motors are employed they may be controlled simultaneously or independently by a suitable switch mechanism (not shown) secured to the machine 70 in any convenient location, or, if desired, and as previously described the screws 172 may be actuated by hand. The work carriage is arranged to be moved so as to present the work carried thereby to the end facing tools and to carry the 75 work between these tools so as to face off both

ends of the work and reduce it to a predetermined length. After this is accomplished, the workholder is manipulated to present the work between the center drills 8 and 9 and there hold it while the center drills are caused to center the ends of the work and retract therefrom, whereupon the work may be released and a new piece inserted. This motion of the workholder is shown as produced by a pair of former cams 205 (see Figures 1, 4 and 3) which are secured to a carriage 206 mounted to slide on a track member 207 (see Figure 4). This track member is shown as secured to the forward face of the bed 1 as by a pivot 208. It may be adjusted for elevation at opposite ends and thus angularly above its 10 pivot by means of screws 209 threaded into its lower face and bearing on a horizontal shoulder or ledge 210 extending outwardly from the base portion of the machine. These former cams 205 cooperate with cam followers 212 suitably secured to the forward ends of the carriage parts 4 and the former cams 205 have inclined faces so that by moving the carriage 206 axially the forward end of the carriage part 4 is positively moved upwardly or allowed to descend by gravity, the 15 followers 212 riding on the faces of the former cams 205. The carriage 206 is reciprocated in proper timed relation to perform the machine cycle and for this purpose it has pivoted at its head stock end thereto at 215 a rod 216 secured 20 to a slidable block 217 which carries a suitable cam follower 218 with which cooperate cams 219 and 220 fixed to the cam drum 221. Means are provided by which the initial motion of the workholder to present the work to the end facing tools is accomplished quickly whereupon the motion is slowed while the work is being carried between the facing tools. When this has been completed, the work is returned with fast motion to a position opposite to the centering drills where 25 it is held stationary during the center drilling operation and while the work is released and new work placed in position. After the drilling operation is completed the machine is automatically stopped. To these ends a two speed drive 30 for the cam shaft 126 is provided, this two speed mechanism being controlled by cams on the drum 127, other cam mechanism carried by the cam shaft 126 also serving to automatically stop the machine at the end of its cycle of operations. 35 The cam drum 127 has secured thereto a worm wheel 230 (see Figure 8) with which meshes a worm 231 on a transverse cam drive shaft 232. One end portion of this shaft 232 has journalled thereon a sleeve 233 which carries a bevel gear 234 meshing with a similar bevel gear 235 on the lower end of a vertical jack shaft 236. The upper end of this shaft 236 has secured thereto a bevel gear 237, which meshes with the bevel gear 238 on the shaft 83. This jack shaft 236 40 constitutes the high speed drive shaft and the sleeve 234 driven thereby is arranged to be selectively clutched to the cam drive shaft 232 through the multiple ring clutch shown at 240. This clutching and unclutching is effected by axial motion of the clutch collar 241. This clutch collar is moved by a suitable clutch actuating fork 242 which, as shown in Figure 14, is carried by a rock shaft 243. This rock shaft has secured thereto an arm 244 which is connected 45 through a link 245 to a rod 246 (see Figure 15). This in turn is connected to an arm 247 secured to a vertical rock shaft 248 to the upper end of which is secured an arm 249 having a cam follower 250 thereon with which cooperates suit- 50

able cams (not shown) on the drum 127, it being understood that these cams are so arranged as to actuate the clutch to couple the high speed drive shaft 236 to drive the drum during the fast motion portions of the work carriage movement and to unclutch this connection during the slow speed portions of the work carriage movement. When the high speed clutch is unclutched the cam drive shaft 232 is driven at a slower speed through connections at its opposite end. As shown in Figure 8 these comprise a gear 255 journaled on the shaft 232 and connected through an overrunning clutch mechanism of any suitable type at 256 therewith so that the shaft 232 can run ahead of the rotation of the gear 155 when driven by the high speed mechanism, but is automatically clutched to be driven by the slow speed drive when the high speed drive is unclutched therefrom. This gear 255 is in mesh with a bevel pinion 257 fixed to a vertical jack shaft 258 on the opposite side of the machine to the high speed jack shaft 236. To the upper end of this shaft 258 is keyed a stub shaft 259 which has keyed thereto one of a pair of change gears 260 housed within a change gear box 261. This change gear 260 meshes with another change gear 262 on a vertical shaft 263 which also has keyed thereto a bevel gear 264 which meshes with a gear 265 (see Figure 10) on a shaft 266. This shaft in turn carries the bevel gear 267 with which meshes a bevel gear 268 fixed to the shaft 35. The gears 261 and 262 being change gears are mounted so that they may be removed and intermeshing gears of different relative sizes substituted therefor in order to predetermine the rate of the slow speed. For this purpose the shafts 259 and 263 may be lifted to raise the change gears out of the box 261. The mechanism may be thrown from high into low speed or vice-versa by means of the handle 269 secured to the member 249. This drive for the cam drums is similar to that fully described in my Patent No. 1,923,493, for Lathe granted August 22, 1933.

The automatic stopping of the machine is also controlled by suitable cams on the drum 127 through an arm 270 (see Figure 15) pivoted at 271 at the head stock end of the machine, and which carries a cam follower 272. To the outer end of this arm 270 is pivoted at 273 the lower end of a link 274 the upper end of which is pivoted at 275 to an arm 276 fixed to a rock shaft 277. This rock shaft 277 extends along the forward face of the head stock casing and remote from the arm 276 it carries a crank arm 278 which is connected through a link 279 with an arm 280 on a horizontal rock shaft 281. This rock shaft carries an arm 282 provided with a latch lug with which cooperates a latch 284 carried by the starting lever 90. The latch 284 is spring-pressed in a well-known manner so that when the lug 283 is in raised position the lever 90 may be thrown past the latch lug to start the machine and will be retained in machine operating position by engagement of the latch 284 on the lug 283 until such time as the end of machine operation has been reached whereupon the stop cams on the drum 127 will through the connections described rock the lug 283 out of engagement with the latch 284, releasing the handle 90 whereupon the spring 13 will disconnect the main driving clutch and apply the brake as has heretofore been described. The rock shaft 281 has a handle 285 by which it may be turned by hand to trip the handle 90 and stop the machine.

The high speed jack shaft 236 may also be employed to drive the coolant pump, connection for this being shown in Figure 14 where the bevel gear 235 is shown as meshing with a bevel gear 290 on the pump shaft 291, the pump being indicated at 292, the intake pipe 293 for which extends into the stump 294.

From the foregoing description of an embodiment of this invention it should be evident to those skilled in the art that various changes and modifications might be made without departing from the spirit or scope of this invention as defined by the appended claims.

I claim:

1. A machine for preparing work to be turned between centers, comprising a pair of spaced rotary end facing tools, a pair of oppositely disposed center drills in fixed transverse relation to said tools, a movable work carriage, means on said carriage to grip work, means for moving said carriage to pass work thereon between said facing tools to face off the ends of the work and reduce it to a predetermined length and then to present the work between said drills, means for then actuating said drills to center drill the work, and mechanism for automatically actuating said means in timed relation.

2. A machine for preparing work to be turned between centers, comprising two pairs of rotary spindles, the spindles of each pair being in spaced axial alignment, end mills carried by the adjacent ends of the spindles of one pair, opposed centering drills carried by each spindle of the other pair, a workholder, means for moving said workholder to move the work laterally of said spindles between said end mills to face off the ends of the work and to reduce it to a predetermined length and then to present the work between said drills, means acting to move said drill spindles axially toward and then from each other to center drill the work in said faced ends and then to retract therefrom, and mechanism for automatically actuating said means in timed relation.

3. A machine for preparing work to be turned between centers, comprising two pairs of rotary spindles, the spindles of each pair being in spaced axial alignment, end mills carried by the adjacent ends of the spindles of one pair, opposed centering drills carried by the adjacent ends of the spindles of the other pair, a work carriage rockable about an axis parallel to said spindles, means on said carriage to grasp work, means for rocking said carriage to pass work carried thereby between said mills to face off the ends of the work and to reduce it to one predetermined dimension and then to present the work between said drills, and means acting to feed said drills toward and from each other to center drill said ends and then retract therefrom.

4. A machine for preparing work to be turned between centers, comprising a pair of spaced end facing tools, a pair of oppositely disposed center drills, a movable work carriage, means on said carriage to grip work, means for moving said carriage to pass work thereon between said facing tools to face off the ends of the work and reduce it to a predetermined length and then to present the work between center drills, means for then actuating said drills to center drill the work, a cam shaft, and cams on said shaft for controlling said carriage moving and said drill actuating means.

5. A machine for preparing work to be turned between centers, comprising a pair of end facing

tools spaced apart the desired length of the work, a pair of oppositely disposed center drills, a work-holder, means for moving said holder to bring work thereon up to said tools under fast motion, 5 to pass the work between said tools to face off its ends under slow motion, then under fast motion to present the work between said drills and there to hold it, and means for then actuating said drills to center drill said work ends.

10 6. A machine for preparing work to be turned between centers, comprising a pair of end facing tools spaced apart the desired length of the work, a pair of oppositely disposed centering drills, a workholder pivotally mounted on an axis parallel 15 to those of said drills, a former cam movable substantially parallel to said axis for controlling the angular position of said holder, a cam shaft, cams on said shaft for controlling and moving said former cam to cause work on said holder to be passed between said facing tools to face the ends of the work to said desired length.

20 7. A machine for preparing work to be turned between centers, comprising a pair of end facing tools spaced apart the desired length of the work, a pair of oppositely disposed centering drills, a workholder pivotally mounted on an axis parallel 25 to those of said drills, a former cam movable substantially parallel to said axis for controlling the angular position of said holder, a cam shaft, cams on said shaft for controlling and moving said former cam to cause work on said holder to be passed between said facing tools to face the ends of the work to said desired length.

30 8. A machine for preparing work to be turned between centers, having head and tail stocks, means for adjusting the spacing of said stocks, a rotary end facing tool and a center drill carried by each stock, means for rotating said tools and drills, a workholder having work grasping portions spaced adjustably lengthwise of the work, and means for automatically moving said workholder to present the work successively into operative relation to said tools and drills and to feed said drills toward and from work held by said grasping portions.

35 9. A machine for preparing work to be turned between centers, having head and tail stocks, rotary end mills carried by said stocks, opposed center drills carried by said stocks, means for passing work between said mills to face off the ends of said work and reduce it to a predetermined length, mill and drill driving means in said head stock, 40 and connections extending between said stocks for driving said tail stock mill and drill from said mill and drill driving means.

45 10. A machine of the class described, a work carriage, opposed work gripping means movable on said carriage from and toward each other, and a torque motor for moving said gripping means simultaneously toward or from each other.

50 11. A machine of the class described comprising a pair of end facing tools spaced apart the desired length of the work, a work holder pivotally mounted on an axis substantially parallel to the line of spacing of said tools, a former cam movable substantially parallel to said axis for controlling the angular position of said holder, a cam

shaft, and cams on said shaft for controlling and moving said former cam to cause work on said holder to be passed between said facing tools to face the ends of the work to said desired length.

5 12. A machine for preparing work to be turned between centers, comprising a work holder, oppositely disposed spaced center drills, a drive shaft, connections from said shaft to said drills for driving said drills simultaneously in opposite directions, means for moving said drills axially from and toward each other to center-drill opposite ends of the work and to retract therefrom, and means for relatively moving said drills and work holder laterally of the work axis to present and remove work to and from axial alinement 10 15 with said drills.

12. A machine for preparing work to be turned between centers, comprising two pairs of rotary spindles, the spindles of each pair being in spaced axial alinement, rotary end cutting tools carried 20 by the adjacent ends of the spindles of one pair, opposed centering drills carried by each spindle of the other pair, a drive shaft, connections from said shaft for driving all of said spindles including reverse direction connections for said center drill spindles, a work holder, and means for relatively moving said holder and spindles to first face off the ends of work carried by said holder, and then to center-drill the ends of the work.

13. A machine for preparing work to be turned between centers, comprising a pair of heads, a pair of spindles journaled in each head in fixed relation, a rotary cutting off tool carried by one of said spindles in each head, a center drill carried by the other of said spindles in each head, 35 the two drills being in axial alinement, a driving shaft extending between said heads, driving connections from said driving shaft to said spindles including reverse rotation connections to said drills whereby one is rotated in the opposite direction to the other, a work holder, means for moving said holder to first present work between said cutting off tools to reduce the work to a predetermined length and then to present the work in operative relation to said drills, and means for 40 then moving said drills axially to center-drill opposite ends of the work.

14. A machine for preparing work to be turned between centers, comprising a pair of end facing tools spaced apart the desired length of the work, a pair of oppositely disposed center drills, a work holder, means for moving said holder to bring work thereon up to and between said end facing tools to face off said ends and then between said drills and there hold it, means for then actuating said drills to center-drill said work ends and retract therefrom, and means for then automatically stopping the machine.

50 55 JOHN E. LOVELY.
